US0D1008580S

(12) **United States Design Patent** (10) **Patent No.:** **US D1,008,580 S**
(45) **Date of Patent:** **** Dec. 19, 2023**

(54) **RECHARGEABLE POOL CLEANER**

(71) Applicant: **Kokido Development Limited**,
Kowloon (HK)

(72) Inventor: **Jean Julien Bruneel**, Kowloon (HK)

(73) Assignee: **Kokido Development Limited**,
Kowloon (HK)

(**) Term: **15 Years**

(21) Appl. No.: **29/755,135**

(22) Filed: **Oct. 17, 2020**

(30) **Foreign Application Priority Data**

Jun. 5, 2020 (CN) 202030277794.2

(51) **LOC (14) Cl.** **15-05**
(52) **U.S. Cl.**
USPC **D32/15**

(57) **CLAIM**

I claim the ornamental design for a rechargeable pool cleaner, as shown and described.

DESCRIPTION

FIG. 1 is a back view of the rechargeable pool cleaner of the present design;

FIG. 2 is a front view of the rechargeable pool cleaner of the present design;

FIG. 3 is a right view of the rechargeable pool cleaner of the present design;

FIG. 4 is a left side view of the rechargeable pool cleaner of the present design;

FIG. 5 is a bottom view of the rechargeable pool cleaner of the present design;

FIG. 6 is a top view of the rechargeable pool cleaner of the present design; and,

FIG. 7 is a perspective view of the rechargeable pool cleaner of the present design.

The dash lines included, if any, depict the environment and are not part of the claimed design.

1 Claim, 7 Drawing Sheets
